UNITED STATES PATENT OFFICE.

GERTRUDE L. NICKERSON, OF BRIDGEPORT, CONNECTICUT, ASSIGNOR TO THE WARNER BROTHERS COMPANY, INC., OF BRIDGEPORT, CONNECTICUT, A CORPORATION OF CONNECTICUT.

COMBINATION GARMENT.

Application filed August 31, 1926. Serial No. 132,731.

This invention relates generally to a garment and more particularly to an article of clothing which combines in the same structure a garment portion designed to function as a corset and a garment portion designed to serve the purposes of a brassière.

5 A general object of the invention is to provide a combination garment of the general type referred to wherein provision is made for adequate expansion to accommodate breathing and, at the same time, a gentle pressure is exerted that controls and suppresses flesh protuberance in the region of the diaphragm.

10 Another object of the invention is to so combine the two garment members that each will effectively perform its functions without interference with the functioning of the other.

15 With these and other objects in view the invention comprises a garment including a corset member having elastic sections in the side portions and preferably also in the lower portion of the forward part. The 20 upper portion of the garment takes the form of a brassière formed as an integral extension of the front and the back portions of the corset member.

25 A feature of the invention resides in the relation of the side portions of the brassière member to the corset member. The side portions of the brassière member terminate at their lower extremities in loose edges, that is, the lower extremities of the side 30 portions of the brassière member are not attached to the adjacent upper extremities of the side portions of the corset member. The upper extremities of the side portions of the corset or girdle member terminate in bands of elastic material which function to 35 provide sufficient pressure in the region of the diaphragm to control protruding flesh. The disconnection, referred to, between the side portions of the corset and the side portions 40 of the brassière permits the application by the corset or girdle member of the desired pressure without causing pressure to be exerted also by the brassière. Preferably the lower and relatively loosely 45 formed edges of the side portions of the brassière are arranged in an underlying position with relation to the upper extremities of the side portions of the girdle member, the looseness of the brassière portions 50 permitting the elastic upper edges of the 55

girdle to stretch as needed to produce the desired pressure on the diaphragm region. Preferably the elastic members or bands are arranged in a slightly inclined position to thereby exert their action in the form of a 60 slightly upward pull or lift.

Other features of the invention will be hereinafter referred to.

In the drawings, in which a preferred embodiment of the invention has been selected for illustration:

Figure 1 is an outside elevation view of a garment embodying the invention;

Figure 2 is a view similar to Figure 1 showing an inside view of the garment;

Figure 3 is a view similar to Figure 1 showing a modified form of the invention;

Figure 4 is a view similar to Figure 2 showing an inside view of the modified form of the invention.

75 Referring to the drawings for a more detailed description of the invention, a garment is shown which comprises a combination of a corset or girdle unit 5 and a brassière unit 6 permanently joined together in 80 the form shown in Figures 1 and 2 to form a unitary article of wear. In Figures 1 and 2 the back section 7 of the corset portion is stitched at its upper terminal edge 8 to the lower edge of the corresponding section 9 85 of the brassière. A similar construction is provided for the forward section 10 of the corset unit and the forward section 11 of the brassière unit, the adjacent edges of which are joined together by the line of 90 stitching 12. The side sections 13 of the corset unit have inserted therein sections 14 formed of elastic fabric and an elastic section is also inserted at 15 in the forward front section 10 of the corset unit.

95 A feature of the invention resides in the relation of the side sections of the two garment units to each other. This feature of the invention includes the provision of a loose lower edge portion 16 formed on the side sections 17 of the brassière unit which are unattached to the upper extremities of the side sections 13 of the corset unit. The lower edges 16 of the brassière section 17 occupy an underlying position with relation to the upper edges of the corset sections 13 which terminate in elastic bands 18 having a position such that the forward ends of the band sections 18 occupy a somewhat lower position in use than the position of

the rearward ends thereof. The inclination thus given to the terminal elastic band sections 18 of the side sections 13 of the corset unit provides a controlling and supporting 5 effect in the region of the diaphragm which is beneficial in preventing unsightly protuberance.

Preferrably the lower extremity 16 of the brassière section 17 is relatively full or loose 10 in order to provide for a limited stretching of the upper terminal portions 18 of the corset sections 13, such as takes place in actual use.

It will be seen that the disconnection between the corset unit and the brassière unit 15 provided in the side sections thereof permits the functioning of each garment without interference by the other. In other words, the upper extremity of the corset unit provides the desired pressure or controlling action 20 unimpeded by a restricting action which would be produced by a complete connection to the brassière unit throughout its upper terminal edge. On the other hand, the functioning 25 of the brassière unit is unrestricted by its connection with the corset unit by reason of the disconnection provided at the terminal portions of the side sections. The result is that the brassière unit obtains at all 30 times a smooth fit without exerting the pressure that is applied by the corset unit.

In the form of the invention shown in Figures 3 and 4 of the drawings, the back portion 19 of the corset unit and the back portion 20 of the brassière unit are formed 35 as a single piece without the line of stitching characteristic of the form of the invention shown in Figure 1. The forward section 21 of the corset unit and the forward section 40 22 of the brassière unit are, however, formed substantially as in Figures 1 and 2.

In this form of the invention, the side sections of the corset unit 23 and the side sections 45 24 of the brassière unit each terminate in elastic band portions 25 and 26. The elastic band portions 25 of the side sections 23 of the corset unit are similar in all respects to the elastic band sections 18 of the form of the invention shown in Figures 1 and 2. However, the elastic band sections 50 26 which form the lower terminal edges of the side sections 24 of the brassière unit form a feature of the invention which is not shown in Figures 1 and 2. The elastic band sections 55 26 lie within the terminal band section 25 of the corset unit and are arranged at an inclination such that the forward portions thereof are at a higher level than the back portions thereof in use. This arrangement and disposition of the lower terminal section 60 26 of the side portions 24 of the brassière unit provides a useful compressing or restricting action in a desired direction.

It will be seen that the combination garment described is so constructed as to com-

bine in one garment the useful features of two garments and without interference of either unit with the functioning of the other. The brassière unit functions in its own way to provide the necessary expansion accompanying breathing while at the same time the adjacent upper portion of the corset unit exercises the desired pressure in the region of the diaphragm. The disconnection between the two garment units between the 70 side sections thereof provides for the form controlling functions of the upper portion of the corset unit in the region of the waistline without interfering with a desirable smooth fit of the brassière portion. 80

The introduction of elastic material in the waistline zone of the improved garment provides for the expansion and contraction at the diaphragm which is necessary for easy and comfortable breathing. This structural arrangement contributes materially to the comfort and health of the wearer and at the same time avoids a looseness and lack of support that would result in the development of an unsightly roll of flesh. 90

There are also additional advantages in the structural arrangement wherein the side sections of the corset and the brassière sections are disconnected from each other. It will be seen that the wearer of the garment 95 can lean or bend sideways without an accompanying wrinkling or bunching of the garment at the side toward which the body is bent, since the disconnected adjacent edges of the side sections are free to slide with relation to each other. At the same time the disconnected condition of the upper edge of the side section of the corset unit and the lower edge of the brassière unit at the other side of the wearer permits upward stretching or leaning without corresponding stretching and pulling of the material in the garment. 100 105

The terms and expressions which I have employed are used as terms of description 110 and not of limitation, and I have no intention, in the use of such terms and expressions, of excluding any mechanical equivalents of the features shown and described, or portions thereof, but recognize that various 115 structural modifications are possible within the scope of the invention claimed.

What I claim is:

1. In a combination garment, a corset unit and a brassière unit having the upper extremities of the front and rear sections of the corset unit attached to the lower extremities of the front and rear sections of the brassière unit, the side sections of the two units being unattached to each other, the main body portion of the side sections of the corset unit being formed of non-elastic material and the upper edges of the sections being formed of elastic material, and located outside of and in overlapping 120 125 130

relation to the lower edges of the side sections of the brassière unit.

2. In a combination garment, a corset unit and a brassière unit having the upper extremities of the front and rear sections of the corset unit attached to the lower extremities of the front and rear sections of the brassière unit, the side sections of the two units being unattached to each other, 10 the main body portion of the side sections being formed of non-elastic material and the upper extremities of the side sections of the corset unit being formed of bands of elastic material arranged to overlie the lower 15 extremities of the side sections of the brassière unit, said bands of elastic material being arranged to occupy an inclination such as to produce an upward and rearward pull in the front section of the corset unit.
- 20 3. In a combination garment, a corset unit and a brassière unit having the upper extremities of the front and rear sections of the corset integrally attached to the lower extremities of the front and rear sections 25 of the brassière unit, the side sections of the two units being unattached to each other and arranged in overlapping relation at their adjacent extremities, the lower extremities of the side sections of the brassière unit 30 being loosely formed the main body portion of the side sections being formed of non-elastic material, and the upper extremities of the side sections of the corset unit being formed of bands of elastic material arranged 35 to overlie the lower extremities of the side sections of the brassière unit, said bands of elastic material being downwardly inclined
- toward their forward ends whereby to produce an upward and rearward pull at the waistline portion of the front section of the 40 corset unit.
4. In a combination garment, a corset unit and a brassière unit having the upper extremities of the front and rear sections of the corset unit attached to the lower extremities of the front and rear sections of the brassière unit, the side sections of the two units being unattached to each other and arranged in overlapping relation at their adjacent extremities, the lower extremities 45 of the side sections of the brassière unit being formed of bands of elastic material inclined upwardly at their forward ends, and the upper extremities of the side sections of the corset unit being formed of 50 bands of elastic material inclined downwardly at their forward ends.
5. In a combination garment, a corset unit and a brassière unit having the upper extremities of the front and rear sections of the corset unit attached to the lower extremities of the front and rear sections of the brassière unit, the side sections of the two units being unattached to each other, the main body portion of the side sections of 55 the brassière unit being of non-elastic material and the lower extremities thereof being formed of bands of elastic material arranged to underlie the upper extremities of the side sections of the corset unit, said bands of elastic material being upwardly inclined 60 toward their forward ends.

GERTRUDE L. NICKERSON.
